PRINTING TELEGRAPH APPARATUS

Albert H. Reiber, Evanston, Ill., assignor to Teletype Corporation, Chicago, Ill., a corporation of Delaware

Application March 3, 1938, Serial No. 193,642

25 Claims. (Cl. 178—29)

This invention relates to printing telegraph apparatus and particularly to printing telegraph apparatus in which the characters are printed in page form from type elements carried upon the periphery of a rotatable and selectively arrestable wheel.

An object of the invention resides in the provision, in a printing telegraph receiving unit embodying a selectively rotatable type wheel, of instrumentalities for effecting printing therefrom independently of a succeeding selective operation for determining a subsequently selective position of the type wheel.

Another object of the invention is to render each character visible immediately after it is printed and further to render all of the printed material at the printing level visible when the receiving unit is at rest.

Another object of the invention is to provide separate terminal blocks and slip connection blocks for the electrical apparatus included in each assembly of apparatus that is removable as a unit from the receiving printer, so that partial dismantling of the apparatus may occur without interfering with the circuits to apparatus not involved in the dismantlement.

The invention features, in a printing telegraph receiving unit embodying a type wheel, independently driven instrumentalities for setting the final selector mechanism and for printing, which instrumentalities operate successively to accomplish the printing of a character in response exclusively to the control signal representing the particular character.

Specifically, the invention features a division of the transfer and printing control operation between two cam assemblies that are independently driven, the establishment of a driving connection for one of the cam assemblies being controlled by the other cam assembly.

The invention also features an arrangement for oscillating the type wheel, whereby it is projected into position for printing just prior to the printing operation and is retracted from that position following the printing operation, so that a character which has been printed becomes immediately visible after printing and all of the characters previously printed in a line are brought into view at the same time.

In a copending application Serial No. 77,796 filed May 4, 1936 by Albert H. Reiber, there is disclosed a type wheel printer with reference to which the present invention stands as an improvement. According to the disclosure of that application, the transfer operation, by which the

code discs of a code disc selector are set in accordance with a new signal combination and the type wheel is released for rotation to a new position of arrestment corresponding to the transferred signal, is performed by a cam included in a cam assembly which also includes the cam for performing the printing operation. The printing operation is timed to precede the transfer operation, the reason for this being that the interval of time which it is necessary to allot to rotation of the type wheel to a new position of arrestment might be longer than the interval of time between the transfer operation and the end of the cycle of the cam assembly which includes the transfer and printing cam, so that the printing operation could not be timed to be performed before the end of the cycle in which the transfer occurred. Consequently, the printing operation is timed to occur substantially immediately after the beginning of the next cycle of operation of the cam assembly, and the result is, as described in the copending application, that the printer always comes to rest with a signal combination stored in the code disc selector mechanism which would not be cleared out until the next cycle of operation of the cam assembly. If the signal combination which is stored represents the last character of a message, it is necessary to introduce an idle operation of the printer in order to print the character for the selection of which the type wheel has been rotated in response to the signal combination stored in the code disc selector.

According to the present invention, the cam which effects the transfer has been removed from the cam assembly which includes the print cam and has been included in an extra cam assembly carried by an extra power driven shaft located at the front of the machine. A clutch is provided for connecting the front cam assembly to the shaft by which it is carried, and this clutch is tripped by a cam projection included in the selector cam assembly, the function of which in the receiving mechanism, disclosed in the copending application, was to trip off the clutch for the main cam assembly. The cam assembly carried by the front shaft includes a cam for tripping the clutch through which rotation is imparted to the cam assembly on the main shaft, which includes the print cam. The front cam assembly, when it has effected the transfer and has come to rest, has set in operation the main or inner cam assembly and the printing of the character represented by the signal which has been transferred occurs before the main cam assembly comes to rest. Thus a complete cycle of operation of

the receiving mechanism, which begins with the reception of the start impulse of a signal combination and which terminates when the main cam assembly comes to rest, occupies a greater interval of time than does a cycle of operation of the receiving mechanism shown in the copending application, but there is no storage of a signal combination necessitating the introduction of an idle cycle, and signal combinations may be received and rendered effective for the printing of characters or the performance of functions as rapidly as in the printing mechanism according to the disclosure of the copending application.

An arrangement for rendering each character visible immediately after printing is included in the present invention, the immediate visibility of the character being accomplished by normally holding the type wheel below the printing line, lifting it into printing position just prior to the performance of the printing operation and lowering it to the normal or rest position thereafter. The lifting and lowering of the type wheel is controlled by two cams, one included in the cam assembly on the front shaft and the other included in the cam assembly on the main or inner shaft. The cam on the front shaft operates in advance of the tripping off of the clutch through which the cam assembly on the main shaft is driven, to elevate a frame which holds the type wheel hub until the frame is arrested under the control of a mechanism which is controlled in accordance with letters or figures printing selection, a selected peripheral arrangement of printing elements being aligned with the printing level when the frame is arrested. Just before the elevating cam comes to rest it loses control over the type wheel supporting frame, but by this time a cam carried by the cam assembly on the main shaft has been rotated into position to assume control over the frame and hold it elevated until the printing operation occurs. After the character has been printed, this cam controls the lowering of the type wheel frame to its normal or rest position.

The type wheel which is included in the printing telegraph apparatus according to the present invention may be generally of the type disclosed in copending application Serial No. 77,794 filed May 4, 1936 by Howard L. Krum et al. The type wheel has two rows of type pallets having character faces arranged around the periphery of the type wheel. The type pallets are held in the type wheel structure by springs and are arranged to be driven radially of the type wheel by a print hammer. When the type wheel is elevated preparatory to printing, one or the other of the two rows of type pallets is brought into position level with the offset end of the print hammer, so that when the print hammer is operated, it will drive the particular type pallet which is in direct alignment with it radially of the type wheel to strike a message receiving page carried by the printing platen. The print hammer is reciprocated to effect printing by operation of the print cam acting through a cam follower arm and a bail.

Certain features of invention disclosed but not claimed herein are also disclosed and are claimed in copending applications Serial No. 208,761, filed May 19, 1938, by Edward S. Larson, Serial No. 204,038, filed April 25, 1938, by Carl A. Levin, Serial No. 203,021, filed April 20, 1938, by Berthel F. Madsen, Serial No. 210,816, filed May 31, 1938, by Carl W. Swan, and Serial No. 211,496, filed June 3, 1938, by Herman Lotterman.

For a complete understanding of the invention reference may be had to the following detailed description, to be interpreted in the light of the accompanying drawings, wherein

Fig. 1 is a perspective view of the combined transmitting and receiving mechanism according to the present invention, certain portions being broken away to clarify the showing;

Fig. 2 is a front elevational view of the receiving and printing mechanism;

Fig. 3 is an elevational view of the receiving printer taken at the right-hand side thereof;

Fig. 4 is a view taken from the top showing sections taken on various planes to show constructional details, and

Fig. 5 is an exploded view in perspective of the type wheel oscillating mechanism and the relationship of the shift and unshift function mechanism thereto.

Referring now to the drawings and particularly to Fig. 1, the reference numerals 16 and 17 designate generally the typing unit and keyboard transmitter unit, respectively, of a printing telegraph apparatus embodying the present invention. The keyboard transmitter unit 17 is generally similar to the transmitter disclosed in copending application Serial No. 77,796, filed May 4, 1936 by Albert H. Reiber, and typing unit 16 embodies improvements on the typing unit disclosed in the copending application.

The foundation of the keyboard transmitter unit is the base casting 18 to the forward vertical wall of which is secured a slotted comb 19. A plurality of key levers 21 are pivoted within the casting 18 for rocking movement in a vertical plane, and these key levers protrude from the interior of base 18 through a slot in comb 19. The key levers 21 are provided with keytops 22 and are arranged to impart characteristic settings to permutation code bars contained within base 18 as fully disclosed in Patent No. 1,595,472 granted August 10, 1926 to Howard L. Krum. To the code bars are articulated lock levers 23 pivotally supported intermediate their ends and projecting above the upper surface of base casting 18 through apertures therein. The lock levers 23 are therefore subject to permutative setting by the code bars under the control of key levers 21.

The upwardly projecting portions of the lock levers 23 are disposed between brackets 24 and 26 secured to base 18, and aligned with each of the lock levers 23 is a contact controlling lever 27, the levers 27 being pivotally supported by a pivot rod (not shown) extending between brackets 24 and 26. A transmitting contact spring 28 individual to each of the levers 27 is mounted between insulating strips upon laterally extending portions of brackets 24 and 26, as indicated at 29. The upper end of each contact spring 28 engages a gooseneck portion of lever 27 and the flexing of contact spring 28 into and out of engagement with a shorter associated contact spring is controlled by gooseneck lever 27. The rocking of the gooseneck lever 27 is, in turn, controlled by the lock levers through blocking lugs (not shown), a lever 27 being unblocked when its corresponding lock lever is presented in extreme clockwise position and being blocked when its corresponding lock lever is in extreme counterclockwise position.

Bracket 24 and another bracket designated by the reference numeral 31 rotatably support a signal transmitting distributor shaft 32. Near one end shaft 32 has secured thereto a gear 33 to which rotation is continuously imparted by an-

other gear as will presently appear. Adjacent to gear 33, shaft 32 has secured thereto the driving element 34 of a jaw clutch. A driven clutch element 36, slideable upon shaft 32, is keyed to a cam sleeve 37 and is urged toward clutch driving element 34 by a compression spring 38. A pivoted clutch throwout lever 39 normally holds driven clutch element 36 out of engagement with driving element 34 against the force exerted by compression spring 38. Clutch throwout lever 39 has an arm 41 which terminates substantially in engagement with an abutment screw 42 carried by a clutch tripping bell crank 43. A depending arm 44 of bell crank 43 has its outer end disposed in the path of a lug 46 carried by a link 47 which enters the keyboard base 18 and is there connected to a universal bail (not shown). When link 47 is shifted forwardly of the keyboard transmitter base by operation of the universal bail under the control of one of the key levers 21, it rocks bell crank 43 clockwise which, in turn, trips clutch throwout lever 39 and permits spring 38 to shift driven clutch element 36 into engagement with driving element 34. As link 47 is moved forward, it is cammed downwardly by cooperation of a cam projection 48 with the head of a screw 49 carried by a forwardly extending portion of bracket 26. The camming of link 47 downwardly permits the free end of arm 44 of bell crank 43 to escape from lug 46 so that bell crank 43 may return immediately to its extreme counterclockwise position and permit clutch throwout lever 39 to return immediately into position for arresting the clutch comprising elements 34 and 36 at the conclusion of one revolution thereof, even though a key lever should be held depressed and link 47 retained in its forward position for a prolonged interval of time. Thus the operation of cam sleeve 37 by the jaw clutch is confined to single revolution in response to each operation of a key lever. A tension spring 51 maintains engagement between cam projection 48 of link 47 and the head of screw 49.

The cam sleeve 37 carries a lock bail operating cam 52 and a plurality of impulse timing cams 53. Cam 52 controls the operation of a lock bail 54 pivotally supported by brackets 24 and 26, lowering the bail into blocking relation to the lock levers 23 as the cam sleeve 37 begins to rotate, and lifting it at the end of a cycle. The function of the lock bail 54 is to prevent the shifting of lock levers 23 during a cycle of rotation of the impulse timing cams 53 and thus preventing mutilation of a signal combination established by the depression of a key lever 21. Each of the cams 53 is aligned with one of the transmitting contact control levers 27 and is engaged by a portion of the aligned lever. Each of the cams 53 has a notch 56 in the periphery thereof which, when presented to the associated transmitting contact control lever 27, releases that lever for rocking movement in counterclockwise direction, and the lever 27 rocks unless restrained by its associated lock lever 23. The recesses 56 in the several cams 53 are arranged spirally about the cam assembly 65 so that the levers 27 are released for rocking movement successively. When a lever 27 is permitted to rock counterclockwise by its cam 53, its contact spring 27 flexes into engagement with the associated short contact spring and a current impulse is impressed upon the telegraph line, the duration of which corresponds to the interval in which the lever 27 remains in its counterclockwise position. The cams 53 thus distribute to the telegraph line the signal impulses corresponding to a

character represented by a key lever depressed. One of the contact controlling levers 27 has no lock lever associated with it and operates invariably once in each cycle of operation of the transmitting cam for impressing on the line the stop impulse.

The principal foundation element of the typing or receiving unit is a casting which mounts on the keyboard base 18 and has a portion 61 located centrally of the base 18 and a portion 62 extending transversely of the base 18 in proximity to the rear edge thereof. Thumb screws are employed for securing the casting comprising portions 61 and 62 to the base 18, one of those screws being indicated at 63. A secondary casting 64 extends transversely of the keyboard base 18 and is secured to portion 62 of the primary casting by any desired means, such as screws. The primary casting supports all of the power driven shafts, the operating cam assemblies, the selector mechanism, the printing mechanism, and the ribbon feed mechanism. The secondary casting 64 supports the platen carriage and associated mechanism, the signal bells, and a set of levers by which various functions are performed.

The primary selector mechanism which integrates the signal combinations generated in the keyboard transmitter mechanism, hereinbefore described, or in a remote transmitter, is indicated generally by the reference numeral 66 and is generally similar to the primary selector mechanism disclosed in the hereinbefore identified copending application of Albert H. Reiber. The principal elements of the selector mechanism 66 are a selector cam assembly 67, a selector magnet 68, and a sword and T-lever assembly 69, the last mentioned assembly as well as the selector magnet being supported by a mounting plate 71 carried by the forwardly extending portion 61 of the primary casting. The selector cam assembly 67 is carried by the upper end of a vertically positioned shaft which is rotatably supported in bearing blocks 72 and 73. The selector cam assembly 67 has flanges 74 secured thereto at opposite ends, and in spaced relation to each flange 74 is a flange 76 secured to the shaft which supports the cam assembly 67. A friction disc 77 occupies the space between each of the flanges 74 and the adjacent flange 76. Considerable friction is generated between the discs 77 and those positioned on either side of them so that selector cam assembly 67 will rotate with its supporting shaft except when restrained under the control of selector magnet 68, as is well known in this type of single magnet selector mechanism.

Just above the point at which it enters lower bearing block 72, the shaft has secured thereto a gear 78. An electric motor (not shown) drives a pinion which meshes with gear 78 so that the shaft to which the gear 78 is secured is continuously rotated. It may be added at this point that a gear 79 carried by a stub shaft meshes with gear 78 and that a spiral gear 81 also secured to the stub shaft meshes with gear 33 carried by the transmitter shaft 32. Thus rotation is imparted to the transmitting distributor shaft 32 from the motor pinion through gears 78, 79, 81, and 33.

The sword and T-lever mechanism 69 is actuated under the joint control of selector cam assembly 67 and the selector magnet 68 to interpret or integrate a series of impulses representing a signal combination preparatory to setting T-levers 82 in accordance with the signal combination. Each of the T-levers 82 engages one

arm of a transfer bell crank 83, the other arm of which is articulated to one of the notched code discs of a code disc selector mechanism indicated generally by the reference numeral 84.

The code disc selector mechanism 84 has a circular arrangement of vertically positioned stop pins 86 which project through slots in the topmost plate of the mechanism. Stop pins 86 are biased inwardly radially of the code disc selector mechanism and near their upper ends 5 they rest against the edges of shiftable notched code discs as is fully disclosed in the copending application of Albert H. Reiber. The notching of the code discs is such that for any permutative setting of the discs under the control of T-levers 82 one only of the stop pins 86 finds presented to it an alignment of notches, whereupon the pin therefor enters the alignment of notches under the influence of its biasing spring, its upper end moving inwardly. A type wheel stop arm 87 clamped to type wheel shaft 88 is of such length that in revolving, it just clears those of the stop pins 86 which are held in their outermost positions by the code discs, but finds blocking its path any pin 86 which has entered an alignment of notches in the periphery of the code discs. The type wheel shaft 88 extends downwardly through the code disc selector mechanism 84 coaxially thereof and receives a continuous torque from the driving motor through any convenient means, such as a gear carried by the shaft 88 and connected thereto by friction discs, the gear being continuously in mesh with the motor pinion. With this arrangement, the shaft 88 is always prepared to rotate and is free to do so when any stop pin 86 which had been previously selected is moved out of the path of the stop arm 87 upon the resetting of the code discs. With this arrangement, shaft 88 may be arrested in any angular position in 10 which stop arm 87 encounters a stop pin 86.

The setting of the T-levers 82 according to the operation of the sword lever mechanism 69 is controlled by a transfer bail 91 which is cam operated as will presently appear. Transfer bail 91 is pivotally supported by an upper mounting screw 92 and by a lower mounting screw which does not appear in Fig. 1. Transfer bail 91 is biased in counterclockwise direction by tension spring 93 and has oppositely extending arms 94 and 95, the former of which is only partially indicated in Fig. 1 but which supports transfer springs, as is clearly indicated in the copending application of Albert H. Reiber, and the latter of which carries a locking blade 97 that cooperates with extensions 98 of T-levers 82. Locking blade 97 ordinarily blocks the extensions 98 of T-levers 82 whether they be presented in extreme clockwise or counterclockwise position. The rocking of transfer bail 91 in clockwise direction to effect the resetting of T-levers 82 is accompanied by withdrawal of locking blade 97 out of the path of movement of T-lever extensions 98. When the transfer has been completed, transfer bail 91 returns to its extreme counterclockwise position and locking blade 97 is restored to locking position with respect to extensions 98.

The front portion 61 of the primary foundation casting for the typing unit has secured thereto spaced brackets 101 and 102. A shaft 103 is rotatably supported in vertical position between brackets 101 and 102. Shaft 103 has secured thereto near the lower end a gear 104 which permanently meshes with a gear 106 sup-

ported by gear 78 and secured thereto by any desired means, such as screws. The hub of gear 104 has secured thereto the driving portion 107 of a positive engagement clutch mechanism, the driven portion of which is indicated by the reference numeral 108. The driven element 108 may be of the type disclosed in copending application Serial No. 165,437, filed September 24, 1937, by B. F. Madsen, having in its periphery a groove designated 109 in the present application, which receives the portion 111 of the clutch throwout lever 112. The portion 111 of the clutch throwout lever 112 confines driven clutch element 108 to substantially complete engagement with driving element 107 during a cycle of operation following the tripping of the clutch, and prevents acceleration of the driven element of the clutch from the speed imparted to it by the driving element 107, should any torque generated by negative load resulting from the interaction of a cam follower and its cam be applied to the driven clutch element 108. Driven clutch element 108 is slidably splined or keyed to a cam assembly sleeve 113 and is urged into engagement with driving element 107 by compression spring 114.

Clutch throwout lever 112 is carried by the lower end of a pivoted bail 116, the upper pivot of which is indicated 117. At its upper end, bail 116 is provided with an arm 115, the free end of which is disposed in the path of the lowermost cam projection 120 of selector cam assembly 67. Bail 116 is biased in counterclockwise direction by tension spring 121. When cam projection 120 on selector cam assembly 67 encounters arm 115 of bail 116, the bail is rocked in clockwise direction, thus withdrawing clutch throwout lever 112 from restraining engagement with the driven clutch element 108 of the clutch on the front shaft, and permitting driven element 108 to move into engagement with driving element 107 whereby rotation is imparted to cam sleeve 113.

Cam sleeve 113 supports three cams designated 118, 119, and 125. Cam 119 is engaged by a follower roll 122 carried by an arm 123 secured to transfer bail 91. The direction of rotation of cam sleeve 113 is counterclockwise and cam 119, in being rotated, imparts clockwise rotation to arm 123 and therefore to transfer bail 91. Transfer bail 91, as previously set forth, effects the permutational rearrangement of T-levers 82 and therefore the notched code discs in the code disc selector mechanism 84 in accordance with a signal combination which has been integrated in the sword lever mechanism 69.

As previously set forth, there is a shaft rotatably supported in vertical position by bearing blocks 72 and 73 to which the gear 78 is secured. Below bearing block 73 the shaft has secured thereto the driving element 124 of a positive drive clutch, the driven element of which is indicated 129. Driven element 129 is slidably splined or keyed to a main cam assembly 130 and is urged into engagement with driving element 124 by a compression spring 126. The engagement and disengagement of the elements 124 and 129 of the main cam assembly driving clutch mechanism is controlled by a pivoted clutch throwout lever 127 to which is secured an arm 128 that extends forwardly of the typing unit and terminates in the path of the apex of cam 118 carried by cam sleeve 113 on the front shaft. As indicated in Fig. 1, in which the clutch mechanism on the shaft and on the main cam driving shaft are shown in their rest positions, the rest position of the apex of

cam 118 is a small angular distance in counterclockwise direction from the end of arm 128 which effects the tripping of the main cam clutch comprising elements 124 and 129. Since, as previously stated, cam cylinder 113 rotates in counterclockwise direction, it will be apparent that cam 118 operates upon arm 128 to effect the tripping of driven clutch element 129 just before cam 118 reaches the end of a cycle of operation.

The bracket 101 which rotatably supports the upper end of shaft 103 pivotally supports a bail 131, the pivot being indicated 132. The bail 131 supports a cam follower arm which has been omitted from the showing of Fig. 1 for the reason that it would conceal substantial portions of the main cam assembly 130 carried by the rotatable shaft which is supported in bearing blocks 72 and 73. The cam follower arm carries at its free end a follower roll which engages cam 125 at a point between cam assemblies 113 and 124. The contour of cam 125 comprises a smooth gradual rise and a sharp drop-off, the drop-off being indicated by a reference numeral 133. As cam 125 rotates counterclockwise, it shifts its follower roll away from the axis of shaft 103 and thus imparts a counterclockwise rotation to bail 131. In the rest position of cam 125, the drop-off 133 is a small angular distance beyond the point of engagement of the cam follower roll with cam 125. The tendency of the cam 125 therefore is to permit bail 131 to return sharply to its extreme clockwise position just before cam 125 reaches its rest position. However, as will presently appear, a cam included in the cam assembly 130 assumes control of bail 131 just before the sharp drop-off 133 in cam 125 is presented to its follower, and the cam in cam assembly 130 holds bail 131 in extreme counterclockwise position for a predetermined interval and thereafter controls the restoration of bail 131 to its extreme clockwise position.

Bail 131 has integral therewith an arm 134 which extends toward the rear of the typing unit and terminates in a spring hanger hook 136. Hook 136 supports one end of a tension spring 137, the opposite end of which is connected to an arm 139 of a type wheel supporting frame 139.

Frame 139 is provided with a vertically disposed slot 141, through which extends a stud 142 supported by a portion of the frame of the typing unit. At the top, frame 139 has a horizontally extending portion 143 through which type wheel shaft 88 passes and in which is rotatably held the hub of a type wheel 144. Vertically disposed guide pins 146, only one of which appears in Fig. 1, are supported by a stationary bracket 147 at the top of the typing unit and pass through apertures in the horizontal portion 143 of type wheel supporting frame 139. The pins 146 and the co-operating elements comprising slot 141 and stud 142 permit oscillatory movement of frame 139 vertically, and guide the frame in that movement. Frame 139 is provided with an abutment screw 148 against which arm 134 of bail 131 rests when the bail 131 is in extreme clockwise position and frame 139 is in the lowermost position. When bail 131 is rocked in counterclockwise direction by cam 125, bail arm 134 tends to move out of engagement with abutment screw 148 and spring 137 tends to be distended. Spring 137, in turn, lifts frame 139, and thus type wheel 144, the normal position of which is below the printing line, is elevated so as to bring character elements carried upon the periphery of the type wheel into position to effect printing in line upon

a page carried in engagement with cylindrical platen 149. When bail 131 is restored to its extreme clockwise position, arm 134 engages abutment screw 148 and restores frame 139 to its lowermost position which, in turn, restores type wheel 144 to its lowermost position, whereby each character becomes visible immediately after being printed.

As previously set forth, main cam sleeve 130 is set in operation by the tripping of clutch throwout lever 127 by cam 118 included in front cam assembly 113 just before cam 118 reaches its rest position. The uppermost of the cams carried by cam assembly 130, designated 151, is engaged on the periphery thereof by a follower roll 152 carried at the end of a lever 153 which is pivoted at 154. Lever 153 has integral therewith an arm 156 which is provided near its outer end with a plurality of spring connection apertures 157. Any one of the apertures 157 is adapted to receive one end of a tension spring 158, the other end of which is supported by a spring post 159. Spring 158 biases lever 153 in counterclockwise direction, thus urging cam follower roll 152 into engagement with the periphery of cam 151. The several spring mounting apertures 157 in arm 156 of lever 153 are at different distances from spring post 159 so that the tension exerted by spring 158 and therefore the torque applied to lever 153 may be varied.

A print hammer operating bail 161 is pivotally supported by pivot 162 and coaxially mounted pivot 163. At its lower end, bail 161 is provided with an arm 163 which supports adjustable abutment screw 164 and also one end of a tension spring 166. The inner end of abutment screw 164 engages an arm 167 of lever 153 and the rearmost end of tension spring 166 is also connected to arm 167 of lever 153. With this arrangement, bail 161 tends to occupy extreme clockwise position with respect to lever 153, the extremity of the position being determined by abutment screw 164.

Print hammer operating bail 161 has integral therewith at its upper end a lever arm 168. At its free end, lever arm 168 is loosely articulated to a print hammer 169. Print hammer 169 extends between ribbon spools 171, rotatably mounted upon a ribbon feed mechanism supporting plate 172. Print hammer 169 is provided with upper and lower arms 173 and 174, respectively, which are disposed in the same vertical plane. Lower arm 174 enters a slot in a bracket 176, carried by ribbon feed mechanism foundation plate 172, and by means of slotted bracket 176, print hammer 169 is held in a vertical plane and is guided in reciprocatory motion imparted by arm 168 of bail 161. The upper arm 173 of print hammer 169 is longer than the lower arm 174 and extends across the periphery of type wheel 144 and across the upper end of type wheel shaft 88. At its free end, arm 173 is provided with a depending portion 177 which, in turn, is provided with an arm 178, the location of which is in alignment with the foremost portion of platen 149, which portion is at the level where printing occurs. Print hammer 169 is provided in its lower edge with a shallow recess 170, the base of which rests upon and slides upon a retainer bar 175 secured to ribbon mechanism base plate 172. The motion of print hammer 169 to effect printing is limited by engagement of one end of recess 170 with bar 175, and the restorational motion may, if desired, be limited by engagement of the other end of recess 170 with bar 175.

The print hammer 169 may be lifted out of its position above the type wheel 144 to permit adjusting or changing the type wheel, by springing the free end of print bail arm upwardly until the rearmost end of recess 170 clears bar 175, 5 whereupon arm 174 of the print hammer may be drawn clear of slotted bracket 176, and the print hammer may be rotated upwardly in a vertical plane about its pivot of articulation with bail arm 168.

Type wheel 144 may be generally similar to the type wheel disclosed in the hereinbefore identified application of Albert H. Reiber, and also in application Serial No. 77,794, filed May 4, 1936, by Howard L. Krum et al. As shown in those co-pending applications and as clearly indicated in Fig. 1 of the present application, type wheel 144 is provided with a plurality of radially disposed type pallets 179 which are reciprocably mounted in radial slots in type wheel 144, and are provided at their outer ends with type elements 181. There may be two superposed rows of type pallets 179, and by means of the lifting of type wheel supporting frame 139 by lever 134, either of the rows of type pallets may be brought into alignment with rearwardly presented portion 178 of print hammer 169. For any angular position of arrestment of type wheel 144 by the cooperation of type wheel stop arm 87 with a selected stop pin 86, two of the type pallets 179 will be directed toward platen 149 in the same vertical plane as print hammer 169. According to the distance that type wheel 144 has been lifted by lever arm 134, the distance being controllable, as will appear later, one or the other of the type pallets 179 will be disposed directly in the path of portion 178 of print hammer 169.

Cam 151, in its normal or rest position, holds print bail operating lever 153 in extreme clockwise position in opposition to the tension of 40 spring 158. Spring 166 holds print hammer bail 161 in extreme clockwise position with its abutment screw 164 in engagement with arm 167 of print bail operating lever 153. Thus, print hammer 169 is held in retracted position. At a pre-determined time in the operation of cam 151, a sharp drop-off is presented to follower roll 152 of print bail operating lever 153. When the drop-off is encountered, lever 153 is rocked sharply in 45 counterclockwise direction by spring 158. Lever 153 imparts counterclockwise movement to bail 161 through abutment screw 164. The angular distance through which lever 153 rocks, as cam follower 152 descends to the lowest or innermost point on the periphery of cam 151 is just short of sufficient to drive print hammer 169 positively against the type pallet 179 aligned therewith. However, the inertia of bail 161 and print hammer 169 causes spring 166 to yield and abutment screw 164 to move out of engagement with arm 167. Thus print hammer 169 overtravels or moves a greater distance than it would if positively interconnected with lever 153, the overtravel being caused by the inertia of bail 161 and print hammer 169, and being permitted by spring 166.

As soon as the energy generated by the inertia of bail 161 and print hammer 169 has been expended, spring 166 withdraws print hammer 169 in the direction of its retracted position until abutment screw 164 returns into engagement with arm 167 of lever 153. The remainder of the movement of print hammer 169 to its rest position is effected by the restoration of lever 153 to its extreme clockwise position by cam 151. The

overtravel in the movement of print hammer 169 is sufficient to reciprocate the aligned type pallet 179 radially of type wheel 144 to effect printing. During the period of overtravel and restoration, the free end of arm 173 of print hammer 169 is presented between the type pallets adjacent to that which is being operated, so that the type wheel 144 could not be rotated, even if permitted to do so by arm 87, due to the fact that interference between arm 173 of print hammer 169 and adjacent unoperated type pallet would occur. Spring 166 withdraws print hammer 169 from a position of interference with unoperated type pallets much more rapidly than it could be withdrawn if positively connected to print hammer bail operating lever 153. Thus, with the arrangement hereinbefore described, the print hammer 169 is projected and retracted in the shortest possible interval of time so that more time may be allowed for the rotation of type wheel 144 to the position corresponding to the next selection.

In a preceding paragraph, the lifting of the type wheel to bring either of its two rows of type pallets into printing position was described. The lifting is accomplished by the counterclockwise rocking of bail 131 which has an arm 134 interconnected with the type wheel supporting frame 139 by spring 137. It was stated that the lifting of the type wheel supporting frame 139 is effected by a cam 125 on the front shaft. It was also stated that the lowering of type wheel supporting frame 139 is controlled by a cam included in the cam assembly 130 on the main shaft. This cam is indicated by the reference numeral 186, and is of the internal species having its cam surface on the inside of a depending peripheral flange. The internal cam surface is engaged by a follower roller carried at the free end of an arm 187, secured to type wheel lifting bail 131. Spring 137 biases bail 131 in clockwise direction as previously set forth and, in so doing, urges the follower roller carried by arm 187 to seek engagement with the internal cam surface of cam 186. Cam 186 does not have a restricting channel, so that the follower carried by arm 187 is free to be moved away from engagement with the interior of the depending flange of cam 186 when bail 131 is rocked in counterclockwise direction by cam 125. During the initial stages of the lifting of frame 139 by cam 125, cam 186 may be stationary.

About the time that cam 125 has rocked bail 131 to its extreme counterclockwise position, and before the drop-off of the cam is presented to its follower roller, the innermost portion of the cam surface of cam 186 is presented in engagement with the follower roller carried by cam follower arm 187. During the engagement of the follower roller carried by arm 187 with whatever dwell there may be at the innermost portion of the internal cam surface of cam 186, bail 131 will be held in extreme counterclockwise position and lever arm 134 will be held in a corresponding position. As cam 186 continues to rotate and the receding cam surface is presented to its follower (the recession being radially away from the axis of the cam), bail 131 will be restored by a controlled motion to its extreme clockwise position, and type wheel supporting frame 139 will be restored to its lowermost position to render visible the character just previously printed. It will be apparent that when the type wheel frame 139 is being elevated, the cam follower, by means of which the lowering of the frame will subsequently be controlled, is moved

out of engagement with its cam surface, and that when the frame 139 is being held in elevated position, and is being lowered, the cam follower by which its elevation was accomplished will be held out of engagement with the elevating cam.

Of the principal mechanisms of the typing unit 16, there remains for consideration only the function mechanism. This mechanism is, in general, similar in construction and operation to the function mechanism disclosed in the copending application of Albert H. Reiber, hereinbefore identified. The function mechanism may be understood to include those mechanisms by which such operations shift, unshift, carriage return, line feed, signal bell operation, and transmitter disablement are selected and accomplished. Those functions which are materially different from the corresponding functions, as disclosed in the copending application of Albert H. Reiber, and which will be described in detail, are shift and unshift, by means of which selection of characters in the letters or figures bank of type pallets is accomplished.

The selection of a function is accomplished by means of a testing mechanism which is cam controlled. Since the testing operation can be conveniently performed by a groove or channel cam, a channel 191 is provided in the upper surface of print bail operating cam 151. A cam follower, which could not be shown in Fig. 1, is fitted into the groove or channel 191 in cam 151, and the follower arm is part of a bail 192 which is operated to test for the selection of functions, and to condition in accordance with the selection one or more of a plurality of function bars, indicated generally by the reference numeral 193. The manner in which the presence of a function is tested and in which the function bars 193 are conditioned is fully disclosed in the copending application of Albert H. Reiber.

The function bars 193 are pivotally mounted upon rod 194. Rod 194 is supported between spaced arms 196 and 197, which comprise a function bail pivoted upon pivot rod 198. The lower arm 197 of the function bail has integral therewith an arm 199 at the free end of which is supported a cam follower roller 201. A function cam 202, carried by the main cam sleeve 130, has its periphery engaged by roller 201, and when cam 202 occupies rest position, arm 199 and the function bail comprising arms 196 and 197 are disposed in extreme clockwise position.

At their free ends, the arms 196 and 197 support a spring post 203 to which is hooked one end of each of a plurality of tension springs 204. Each of the springs 204 has its other end connected to one of the function bars 193. Thus, the function bars 193 are biased in counterclockwise direction, and movement of any of them in clockwise direction is opposed by its particular tension spring 204.

The conditioning of function bars 193, under the control of bail 192 in response to a function selection, is manifested by rotation of one or more of the function bars 193 through a small angular distance in clockwise direction. Such rotational movement brings the conditioned function bar out of alignment with the unselected function bars and into position to initiate or perform its assigned function. Immediately after the conditioning of one of the function bars 193, cam 202 rocks its follower arm 201 and the function bail comprising arms 196 and 197 in counterclockwise direction. Since the function bars 193 are pivotally mounted upon

rod 194, carried by bail arms 196 and 197, they are moved endwise toward the rear of the printer as cam follower roller 201 is moved to its outermost position with respect to cam 202. Those of the function bars 193 which have not been conditioned by being rocked in clockwise direction are reciprocated idly while one conditioned function bar 193 initiates or performs the assigned function as a result of the reciprocatory movement. The rod 194, carried by function bail arms 196 and 197, also is pivotally engaged by a spacing pawl 206 which is reciprocated to effect spacing of the platen carriage as the function bars 193 are reciprocated rearwardly of the printer. The spacing operation and the performance of the several functions excepting shift and unshift are sufficiently similar to those disclosed in the copending application of Albert H. Reiber, that it is considered unnecessary to describe them in detail here. However, the shift and unshift functions will now be described.

The hereinbefore identified stud 142, which guides the type wheel supporting frame 139 in its upward and downward movements, extends through a horizontally extending slot in a slide member 207. The slide member 207 is also provided with an open ended slot 208 through which extends a screw 209, carried by the frame of the typing unit. The stud 142 and screw 209 support the slide member 207 and guide it throughout a limited sliding movement forwardly and rearwardly of the typing unit.

The slide member 207 has integral therewith a vertically extending arm 211. The arm 211 is provided near its upper end with a step cut aperture 212. By virtue of the step cutting, two abutments or stop surfaces are provided, the lower of which is indicated by the reference numeral 213, and the upper of which is indicated 214 and is the upper end of the aperture 212. The type wheel supporting and lifting frame 139 has adjustably secured thereto a bracket 216, which has an arm 217, extending into the aperture 212 of the slide member 207. When the type wheel lifting frame 139 is lifted by bail arm 134, operating through spring 137, arm 217 of bracket 216 may encounter either of the stop surfaces 213 or 214, depending upon whether the slide member 207 is presented in its rearmost or foremost position, and thereby the type wheel lifting frame 139 will be arrested in either of two positions of elevation while bail arm 134 continues to be rocked to its extreme counterclockwise position. Then the type wheel lifting frame 139 is arrested by the lower stop surface 213 of slide member 207, the upper row of type pallets carried by type wheel 144 is presented in alignment with the operating extension 178 of print hammer 169, and when the frame 139 is permitted to be lifted until its arm 217 encounters the uppermost stop surface 214, the lower row of type pallets will be presented in alignment with the print hammer 169, and with the character impression level of the platen 120.

The movement of slide member 207 from one to the other of its two positions is accomplished by two levers pivoted upon stud 142, one of the levers being pivotally supported between slide member 207 and the frame elements which support stud 142 and which, therefore, is behind slide member 207 and cannot be seen in Fig. 1, and the other of which is pivotally supported between slide member 207 and type wheel lifting frame 139 and is indicated by the reference numeral 218 in Fig. 1. A screw 219 establishes

a pivotal interconnection between the slide member 207 and its operating lever 218. Lever 218 is provided with a depending finger 221. The first and second of the function bars 193, counting from the top, each have extending laterally therefrom a lug, one of which appears in Fig. 1 and is indicated by the reference numeral 222. The depending finger 221, of lever 218, occupies a position directly in the path of lug 222 when the function bar which carries lug 222 has been conditioned for function performance by being rocked in clockwise direction preparatory to being moved endwise by cam 202, operating through arm 201 and bail arms 196 and 197. When lever 218 is in its extreme counterclockwise position, which is the condition when slide member 207 occupies the rearmost of its possible positions, finger 221 is disposed substantially at the limit of movement of lug 222 so that it will not be affected if the function bar by which lug 222 is carried is conditioned and reciprocated. When, however, the slide member 207 occupies the foremost position, lever 218 will be presented in extreme clockwise position and its depending finger 221 will be positioned to be engaged by lug 222, early in the cycle of movement of that lug rearwardly of the typing unit. Under these conditions, counterclockwise movement of lever 218 by lug 222, as it moves rearwardly of the typing unit, will result in rearward movement of slide member 207 which is articulated to lever 218 by screw 219, whereby slide member 207 will be shifted to its rearmost position with stop surface 213 in the path of arm 217 carried by type wheel lifting frame 139. It will be understood that the timing of the apparatus is such that type wheel supporting frame 139 is held lowered by bail arm 144 when slide member 207 is shifted so that there shall be no interference between arm 217 and the step-cut portion of aperture 212 during the movement of slide member 207.

The restoration of the slide member 207 to its forward position is accomplished by the lever which corresponds to lever 218 and which is pivoted between slide member 207 and the frame member which supports stud 122 so that it does not appear in Fig. 1. A screw 223 establishes a pivotal connection between this lever and the slide member 207. This pivotal interconnection is above stud 142 so that when the lever is rocked in counterclockwise direction, the slide member 207 will be moved forwardly of the typing unit to its foremost position. The lower end of the lever which is pivoted to slide member 207 at 223 may be similar to the lower end of lever 218 so that when it is in extreme clockwise position, it will be disposed in the path of the laterally extending projection of that one of the function bars 193, the function of which is to shift the slide member 207 to its foremost position to permit the type wheel lifting frame 139 and the type wheel 144 to be lifted to their uppermost position whereby printing may be effected from the lower row of type pallets.

It will be apparent from the foregoing description of the levers which control the shifting of slide member 207 that both of these levers effect control by being rocked in counterclockwise direction, one being operative to shift the slide member 207 rearwardly and the other being operative to shift it forwardly. It will also be apparent that as either is rocked in counterclockwise direction by its assigned function bar 193,

the motion which it imparts to the slide member 207 will cause the other lever to be rocked in clockwise direction so that they will be presented alternately in position to be operated by their respective function bars.

In addition to operating the function levers 193 and the spacing pawl 206, the function bail also operates a ribbon feed lever 226. This lever is pivoted upon a stud 227 fixed to a stationary portion of the typing unit and its lower end engages the arms 196 and 197 of the function bail. At its upper end, lever 226 is articulated to a link 228 which has a slot in which is disposed one end of a ribbon feed lever 229. The ribbon feed mechanism which is operated by lever 229 may be substantially identical with that disclosed in the copending application of Albert H. Reiber. The ribbon feed mechanism supporting plate 172 supports pairs of vertically disposed pins 231 which serve as guides for the inked ribbon 232, and there is also a semicircular ribbon guide which is supported by the type wheel lifting frame 139 in spaced relation to the type wheel 144 between the type wheel and the platen 149. Thus, the ribbon guide 233 is lifted each time the type wheel 144 is lifted, and a portion of the ribbon 232 is always positioned between the type wheel 144 and the platen 149 so that inked type impressions may be produced upon a page carried by platen 149.

The platen 149 is rotatably supported by the opposed ends of a carriage 236. The carriage is supported for movement transversely of the typing unit by rails, one of which is indicated as 237, secured to the rear casting member 64. The casting 64 also supports near the top thereof a bracket 238 which has a threaded aperture in coaxial relation to the platen 149. A bushing 239 threadedly engages the aperture in bracket 238 and rotatably supports a square rod 241 which enters platen 149 through one of the hubs therein and passes through a square portion of a tube which extends from end to end of the platen 149. The square shaft 241 is of sufficient length that it may extend into or through the square portion of the tube on the interior of platen 149 in any position which carriage 236 may occupy in its travel back and forth upon its supporting rails. Square shaft 241 has secured thereto a crank 242 which may be rotated manually to impart rotation to square shaft 241 and, through its cooperation with the square portion of the tube into which it extends, rotation may be imparted to platen 149.

Carriage 236 also supports a paper guiding plate or basket 243 which is disposed below the platen for guiding a page in the printing position and which, in turn, supports pressure rolls 244 and paper guide fingers 246. Carriage 236 may have associated therewith character spacing mechanism and line feeding mechanism in accordance with the disclosure of the copending application of Albert H. Reiber. A rotatable drum 247 is provided for housing a carriage return spring. A carriage return belt 248 has one end secured to the periphery of drum 247 and the other end secured to carriage 236.

Terminal blocks and slip connections are provided for connecting the various electrical circuit elements in the keyboard transmitter mechanism and in the typing unit to external circuits. The reference numeral 251 indicates a terminal block which is mounted on the keyboard case casting 18 behind the typing unit. Terminal block 251

has terminals 252 individually engaged by slip connection tongues 253 carried by a slip connection block 254. Slip connection block 254 is secured to the rear portion 62 of the primary typing unit casting below the secondary or carriage supporting casting 64. The contacts 252 and tongues 253 may form electrical connections between the electromagnet 68 carried by the typing unit and the transmitting contact springs 27 carried by the keyboard base and between the selector magnet and external circuit. Thus, the secondary casting and all of the elements which it supports may be removed from the typing unit without disturbing the electrical connection between the selector magnet 68 and the transmitting contacts and between the external circuit and both the selector magnet and the contacts. Also the entire typing unit may be removed from the keyboard base by removal of the thumb screws 63 whereby the slip connection tongues 253 will be removed from engagement with contacts 252 without disturbing the electrical connections between the transmitting contacts and external circuit.

The general operation of the typing or receiving unit hereinbefore described is as follows: Permutation code signals impressed upon a telegraph line to which the receiving unit is connected enter the receiving unit at terminals 252 and slip connection 253 and are impressed upon the selector magnet 68. Gear 78 and the shaft which it drives being in operation, selector assembly 67 which is friction driven is released for a cycle of operation by the start impulse of a signal combination in accordance with the well-known practice employed in the operation of single magnet selector mechanisms controlled by start-stop signals. As the selector cam assembly 67 rotates, the sword levers contained in the sword lever mechanism 69 are set in characteristic positions according to the signal combination received. Just before the selector cam assembly 67 completes a cycle of rotation, its cam projection 128 engages arm 115 of bail 116 and rocks the bail in clockwise direction whereby clutch throwout lever 112 is withdrawn from restraining engagement with driven clutch element 108, carried by the front shaft, whereupon the driven element 108 is shifted into engagement with driving element 107, and cam sleeve 113 is set in operation for a cycle comprising one revolution.

The first operation performed after cam sleeve 113 is set in operation is the clockwise rocking of transfer bail 91, by transfer cam 119, operating through cam follower roller 122 and follower arm 123. Transfer bail 91 operates to set the code discs contained in the code disc selector mechanism 84 in correspondence with the setting of the sword levers. The shifting of the code discs to accomplish the selection of a new stop pin 86 is accompanied by the camming of the previously selected stop pin into unselected position whereby the restraint upon type wheel stop arm 87 is removed and shaft 84 and type wheel 144 rotate to seek a new stop position. At this time, the type wheel 144 is held in its lowermost position by the type wheel lifting bail 131 and bail arm 134.

As soon as the transfer has been accomplished, the selector cam barrel 67 may be released for rotation to effect the setting of the sword levers according to a new signal combination. The timing of the operation of selector cam assembly 67 and of cam sleeve 113 carried by front shaft 103 is such, with respect to the speed of operation of 75

transmitting apparatus, in response to which this receiving mechanism is intended to operate, that the transfer has been effected before the selector cam barrel is released by the start impulse of the next signal combination.

A predetermined interval after the transfer operation has been performed, cam 123 begins to rock type wheel lifting bail 131 in counterclockwise direction and the type wheel 144 is elevated into printing position. The position in which the type wheel will be arrested will be determined by the position occupied by slide member 207. Bail 131 will, however, be rocked to extreme clockwise position regardless of the position in which type wheel 144 is arrested, spring 137 yielding to permit the motion of bail 131 to be completed.

A short angular distance before cam 125 has rocked bail 131 to extreme counterclockwise position, cam 118, carried by cam sleeve 113, engages clutch throwout lever 128 of the clutch which comprises driving element 124 and driven element 129 on the main shaft or inner cam shaft, whereby the main assembly 130 is set in operation. By the time cam 125 has rocked type wheel lifting bail 131 to extreme counterclockwise position, internal cam 186, included in the main cam assembly 130, has assumed control of its follower arm 187, which is carried by bail 131, so that type wheel lifting bail 131 is held in extreme counterclockwise position after cam 125 has come to rest and has relinquished control over bail 131.

The front shaft may be rotated at the same speed as the main shaft so that in the reception of signals continuously transmitted, the cam sleeve 113, carried by the front shaft 103, will have a rest period between cycles of operation equal to the rest period of selector cam assembly 67 between successive code combinations. Cam sleeve 113 may, therefore, begin its next cycle of rotation before the cam assembly 130, carried by the main or inner shaft, has completed much of its cycle of operation. While cam 186 is holding type wheel 144 elevated, and before cam sleeve 113 can have rotated sufficiently far in the next cycle to operate the transfer bail, the print cam 151 brings its sharp drop off into alignment with roller 152, carried by the print bail operating lever 153, whereupon spring 158 rotates lever 153 sharply in counterclockwise direction and this movement is imparted to print bail 161, which drives print hammer 169 into engagement with the selected type pallet and which overtravels sufficiently to produce an impact between the selected type pallet and a message page carried by platen 149. At substantially the same time that print cam 151 permits print bail operating lever 153 to be rocked counterclockwise by its spring 158, cam groove 191, in the upper surface of cam 151, operates its associated bail 192, which tests for function selection as disclosed in the copending application of Albert H. Reiber. The effect of such testing is that a function bar 193, which corresponds to a function that may have been found to be selected is rocked clockwise through a small angular distance in opposition to its biasing spring 204, to bring it into position to initiate or perform its function.

Since tension spring 166 is effective substantially instantaneously after the printing of a character to withdraw print hammer 169 to its retracted position, which operation can be performed much more rapidly by spring 166 than

it could be by cam 151, operating through bail operating lever 153, the transfer of the next signal combination can be performed sooner after the print operation than it could be with positive printing and retraction of the print hammer. The sooner after the printing operation that the transfer of the next signal combination may be performed, the greater is the interval of time that may be allotted for rotation of the type wheel into a new stop position corresponding to the new selection and, therefore, the slower can be the speed of rotation of the type wheel shaft 88. The maintenance of minimum rotational velocities consistent with efficient operation is desirable in order to minimize inertia effects.

Internal cam 186 is required to hold type wheel 144 elevated only until the print operation has been performed. As cam 151 continues to rotate and restores print bail operating lever 153 to its extreme clockwise position, cam 186 permits bail 131 and bail arm 134 to return to extreme clockwise position, the restoration not being abrupt nor violent but rather being controlled and gradual.

As set forth in the description of apparatus, cam 202 operates function bail lever arm 199 to reciprocate the spacing pawl 206 and the function bars 193. Immediately after the printing of a character has been accomplished, the carriage 236 may be spaced to bring a blank portion of the page into position to receive the next character. If instead of a character having been selected for printing a function has been selected, and for the selection evidenced by the clockwise rocking of the particular function bar by operation of bail 192 substantially simultaneously with the operation of print bail lever 153, the apparatus is conditioned for the performance of the function. The operation of lever 199 by cam 202 is gradual so that there is no abruptness in the performance of the function. As the function bars 193 are moved rearwardly of the typing unit by operation of function lever 199, the one of the function bars 193, which has previously been rocked into effective position initiates or performs the function, such as shift, unshift, line feed, carriage return, and various other desirable functions as disclosed in the copending application of Albert H. Reiber. The operation of function bail lever 199 is the last operation performed by the cams on cam sleeve 124 before the cams return to rest position, at which point, clutch throwout lever 121 separates driven clutch element 129 from driving element 124.

From the foregoing it will be observed that during the reception of isolated or widely separated signal combinations, there occurs a train of operations for each signal combination which begins with the setting in rotation of selector cam cylinder 67 and which ends with the arrestment of main cam assembly 130. The selector cam cylinder cooperates with the selector mechanism to set up the signal combination received, trips off the cam sleeve 113 on the front shaft, and comes to rest. The cams carried by sleeve 113 transfer the signal combination to the code disc selector, elevate the type wheel to printing position under the control of the shift and unshift slide member 207, trip off the main cam assembly on the inner shaft, and come to rest. The cams on the main cam sleeve 130 effect the operation of print hammer 169, test for the presence of a function selection, control the lowering of the type wheel to its idle position, effect character

spacing and the performance of any function selected, and come to rest.

When, however, signal combinations are being received at substantially maximum frequency, as is the case when the transmitter from which the signals are being received is operated by a perforated tape, or if it is a keyboard transmitter, being operated by a skillful operator, the stop time between cycles of operation of selector cam assembly 67 will be very brief. The stop time between successive cycles of the front cam cylinder 113 and the main cam cylinder 130 will be correspondingly brief, but definite phase relationships between all of the cam assemblies will be maintained. Thus, all of the cam assemblies may be rotating simultaneously, and not two of them may be at rest at the same time. However, the operations which they control will proceed in orderly fashion exactly in accordance with the planned timing of the receiving mechanism. Any signal combination introduced at the selector magnet 68, whether relating to the printing of a character or to the performance of a function, will have become effective for the purpose for which it was introduced before the completion of the operation initiated by the selector cam assembly 67, and there will be no storage of a signal combination requiring an additional cycle of operation of the selector cam barrel for its clearing out, as is the case in some printing telegraph mechanisms, in which the transfer and printing operations are not assigned to be performed by cams included in separate cam assemblies, but are performed by cams included in a single cam assembly, and in which there is insufficient time between the transfer operation and the end of the cycle of the single cam assembly for the completion of rotation of the type wheel or other conditioning of the printing element and the actual printing operation. In some printing telegraph receiving apparatus having a single operating cam assembly, such for example, as that exemplified in the copending application of Albert H. Reiber, the printing operation is timed to precede the transfer operation in each cycle of the cam assembly so that the printing operation always lags one cam cycle behind the transfer operation, and at the completion of any message, the signal combination for the last character or function remains in storage in the code disc selector mechanism and necessitates the introduction of an idle cycle of the selector cam assembly for its clearing out. In the printing telegraph receiver mechanism according to the present invention, the printing operation and also the operation of the function mechanism follows the transfer operation in the general cycle of operation of the mechanism which may be considered as beginning with the starting of the selector cam assembly 67 into rotation and terminating with the arrestment of the cam assembly 130 carried by the main or inner operating shaft. It will thus be apparent that the printer always clears out and prints in accordance with the last signal combination received and no signal combination is ever left in storage in the selector mechanism.

In the foregoing general description of the printing telegraph apparatus in accordance with the invention, certain details were not described because the description was restricted to Fig. 1 in which those details could not be clearly shown. They are, however, shown in Figs. 2 to 5, inclusive, and will now be described, having reference particularly to the detailed showings.

Type wheel supporting and driving mechanism

Type wheel 144 comprises upper ring element 261 and lower ring element 262 joined by a web portion which has radial slots in which type pallets 179 are slidable. As indicated in Fig. 2, the type pallets are recessed, recesses in those of each row opening toward the recesses of those in the other row, and seated in the recesses of all of the type pallets 179 in a row is a garter spring 263 which biases all the type pallets it engages to their innermost position. The lower ring 262 of type wheel 144 has a cylindrical upset portion 264, the upset portion being coaxial with the type wheel.

The upset portion 264 of type wheel 144 rests on the top of a hub 266, which is slidable upon type wheel shaft 88. At one point in the periphery of type wheel hub 266, there is a notch or recess 267 which receives a pin 268 secured to and depending from the upset portion 264 of type wheel 144. Pin 268, cooperating with slot or recess 267, enables the fitting of a type wheel 144 to hub 266 and, therefore, to shaft 88, in the correct angular position with respect thereto, so that the type wheels may be interchanged without adjustment or the checking of alignment. A plurality of clamping screws 269, which may also be seen in Fig. 4, are employed for rigidly securing type wheel 144 to hub 266.

Hub 266 is supported by type wheel lifting frame 139, and to this end hub 266 is grooved as at 271 to provide a portion of reduced diameter between flanges or shoulders. Intermediate the apertures, through which extend the guide pins or screws 146, frame 139 is provided with a recess which extends inwardly from the foremost edge thereof. This recess is of such width that its defining edges enter the groove 271, and substantially engage the reduced portion of the hub, thereby being disposed between the spaced shoulders. The recess in frame 139, which is entered by the reduced portion of hub 266, need have no closure to insure the retention of the hub, as the location of the type wheel shaft 88 is established, and the position of frame 139 is definitely established by pins 146. From the foregoing it will be apparent that hub 266, while being slidable upon shaft 88, is secured to type wheel shifting frame 139, and in turn has secured to it type wheel 144. Thus, any motion which frame 139 undergoes is imparted to type wheel 144.

Hub 266 has secured thereto, by means of clamping nut 272, a radially extending arm 273 at the free end of which is a depending arm 274. Type wheel shaft 88 has secured thereto, by means of clamping screw 276, a split bushing 277. Bushing 277 has integral therewith a radially extending arm 278, the free end of which is slotted to receive depending arm 274 of type wheel hub arm 273. Rotation is imparted from shaft 88 to hub 266 by means of arm 278 of bushing 277 through the engagement with depending arm 274 of radial arm 273 of hub 266. Arm 274 of hub arm 273 fits freely into the slot in driving arm 278, so that when hub 266 is lifted by frame 139, arm 274 may slide in the slot in arm 278 and thus rotation may be imparted by shaft 88 to type wheel 144 while the type wheel is in motion upwardly or downwardly under the control of frame 139, or while the type wheel is being held in any predetermined horizontal plane.

Function suppression mechanism

In the copending application of Albert H. Reiber, it is disclosed that under certain circumstances, it may be desirable to suppress functions which would otherwise be selected. For example, it has sometimes been the custom to cause the printing of a letter character in response to a particular signal combination if the last preceding case shift signal was an unshift or letters signal, and to cause a function to be performed in response to the same signal if the last preceding case shift signal was a shift or figures signal. It is a simple matter to prevent the printing of a character in response to such signal combination when preceded by a shift or figures combination, it being necessary merely to provide a blank type pallet in the lower row of type pallets at the point where pallet actuation will occur when the print hammer is operated, but it is necessary to suppress the function when printing of a character is to occur from the upper row of type pallets in response to the signal combination when preceded by the letters or unshift signal combination. In the apparatus according to the disclosure of the copending application of Albert H. Reiber, the shifting of the type wheel to its letters and figures positions was accomplished by a type wheel supporting frame which was movable upwardly under the control of the shift or figures function bar, and which remained in that position until restored to its lowermost or letters position by the unshift function bar.

According to the present invention, shift and unshift selections are controlled by the slide member 207 which is slidable horizontally. As indicated in Figs. 1, 3, and 5, slide member 207 has integral therewith a depending arm 281 which terminates substantially adjacent to the lowermost of the function bars 193. Those function bars which relate to the performance of functions which under certain circumstances it may be desired to suppress may be provided with laterally extending projections 282. Depending arm 281 of slide member 207 has secured thereto a function suppression plate 283, which may be step cut on one end and square cut on the other end. When the function suppression plate 283 is secured to arm 281, in the manner indicated in Fig. 3, with the step cut end at the right, and the long portion thereof at the top and slide member 207 is in the unshift or right-hand position, the function suppression plate 283 will block the upper of the projections 282 and will prevent the rocking of the next to the lowest function bar 193 into position to be effective. When, however, the slide member 207 is shifted to its extreme left-hand position, as viewed in Fig. 3, in which position it permits type wheel 144 to be lifted to its uppermost position for figures selection, neither of the projections 282 on the lower function bars 193 will be blocked. The blocking of the projections 282 may be reversed by reversing the function suppression plate 283 so that the edge which is now the upper edge, as it appears in Fig. 3, becomes the lower edge, such reversal being effected without reversing the plate end for end. With this arrangement, the function suppression plate 283 will block neither of the projections 282 when slide member 207 is in position for figures selection, and will block the lowermost of the projections 282 when slide member 207 is positioned for letters selection. If

the plate 283 is reversed end for end so that the square cut end is at the right as viewed in Fig. 3, both of the projections 282 will be blocked when slide member 207 is positioned for letters selection, and neither will be blocked when the slide member is positioned for figures selection.

In the copending application of Albert H. Reiber, there is disclosed apparatus for and a method of suppressing the carriage spacing operation so that when certain functions are selected for performance, the spacing pawl will be prevented from performing a spacing operation. When, however, the space suppression operation is associated with a function which may itself be suppressed under certain conditions, as for example, functions for the suppression of which a function suppression plate 283 may be provided, it may be desirable to prevent the operation of the space suppression mechanism when the performance of the function is suppressed. The reference numeral 284 in Fig. 3 indicates the ends of two levers which, when moved outwardly from the plane of the drawing toward the observer, effect a space suppression operation. Slide member 207 is provided with an arm 286 extending rightwardly, as viewed in Fig. 3, and terminating in a blocking projection 287 and a depending U-shaped portion 288. When slide member 207 is in extreme right-hand position, as viewed in Fig. 3, blocking projection 287 is disposed in the path of movement of the upper of space suppression levers 284 so that, when an attempt is made to operate the upper of levers 284, it will be blocked and spacing pawl 285 will not be disabled. When slide member 207 is shifted to its extreme left-hand position, as viewed in Fig. 3, the right-hand leg 289 of depending U-shaped portion 288 will be disposed in the operating path of the lower of space suppression levers 284 so that it cannot be operated, but blocking projection 287 will have moved out of the path of operation of the upper space suppression lever 284, and it will not be disabled.

Operating cam and follower arrangement

In the general description which had reference particularly to Fig. 1, certain cam followers and their follower arms could not be particularly pointed out and identified due to the fact that it was necessary to omit them from Fig. 1 in order that other elements might be more clearly shown. The cam roller which is disposed in channel 191 of cam 151 appears in Fig. 4 and is indicated by the reference numeral 291. The arm by which it is carried and which imparts motion to function selection testing bail 192 is indicated 292. Reference numeral 293 designates the roller which is operated by type wheel elevating cam 125, and this roller is supported by the free end of arm 294 which is secured to type wheel oscillating bail 131. The arm by which the lowering of the type wheel is controlled is identified, as previously set forth, by the reference numeral 187, and the free end of this arm supports a cam follower roller shown in dotted lines in Fig. 4, and identified by reference numeral 296. This follower roller is engageable with and operable by the internal cam surface afforded by the depending flange of cam 186.

Terminal block and slip connection arrangement

The rear portion 62 of the primary casting 61 is shown in section in Fig. 4 as is also the secondary casting 64. One of the screws by which

5 casting 64 is secured to portion 62 of casting 61 is indicated 301. The method of mounting slip connection block 254 upon portion 62 of the primary casting is shown in detail in Fig. 4 and is observed to comprise screws 302 which extend through slip connection block 254 and threadedly engage portion 62 of the primary casting, spacer bushing 305 being employed to space slip connection block 254 from primary casting portion 62 a distance substantially equal to the thickness of the lowermost portion of secondary casting 64.

10 A slip connection block 303, which may be similar to slip connection block 254, is secured to the lowermost portion of secondary casting 64 by screws 304 which threadedly engage that casting, but which do not extend into nor engage portion 62 of the primary casting. Slip connection block 303 supports a plurality of slip connection tongues 306, which individually engage terminal contacts 307, carried by a terminal block 308, similar to terminal block 251 and similarly secured to the keyboard base casting 18. Electrical circuit apparatus which may be 15 supported directly or indirectly by secondary casting 64 may be connected by conductive wires to the slip connection tongues 306 at their point of support by slip connection block 303. Tongues 306 connect such conductive wires to terminals 307 of terminal block 308 and communication or control circuit wires may be connected to terminals 307 as desired. Thus, electrical connections to apparatus supported by the secondary casting will be confined to blocks 303 and 308. 20 Similarly, electrical circuit apparatus supported directly or indirectly by primary casting 61 may be connected by conductive wires to tongues 253 which, in turn, extend the conductive paths to terminals 252, at which point connection may be made to communication or control circuits. Also, conductive wires may extend from any of the terminals 252 or 307, to electrical circuit apparatus which is supported directly or indirectly by the base casting 18, such as the transmitting 25 contacts. Thus, electrical connections to apparatus supported by primary casting 61 will be confined to blocks 251 and 254. If for any reason it is desirable to remove the secondary casting 64 from rear portion 62 of the primary casting, this may be accomplished by removal of the screws 301. Such removal will result in disengagement of tongues 306 from contacts 307, but the conductive paths which include the slip connection tongues 253 will not be disturbed, as 30 they would be if instead of employing separate slip connection blocks 254 and 303, a single slip connection block had been employed. Similarly, the primary casting 61 may be removed from base casting 18 by removal of thumb screws 63 35 with or without previous removal of casting 64 from casting portion 62, the result being that all of the slip connection tongues 253 and 306 will be removed from engagement with their corresponding terminals 252 and 307 without disturbing the circuits to the transmitting contacts.

Letters and figures shift mechanism

Fig. 5 discloses in detail, by means of an exploded perspective view, the instrumentalities for 40 shifting the slidable member 207 forward and back under the control of the topmost bar 193 which performs the shift function and of the bar immediately below it which performs the unshift function. In the general description which had reference particularly to Fig. 1, the

shifting of slide member 207 to its rearmost position was described as being under the control of lever 218 pivoted upon stud 142, which slidably supports slide member 207, the screw 219 having been identified as the pivotal interconnection between lever 218 and slide member 207. Referring particularly to Fig. 5, it will be observed that lever 218 is provided near its lower end with an elongated slot 311, which is adapted to receive the reduced portion 312 of a cylindrical boss 313, the reduced portion 312 having parallel sides whereby boss 313 is prevented from rotating in slot 311. The slot may be longer than reduced portion 312 of boss 313 to provide for adjustment of the boss with respect to lever 218. Screw 219 threadedly engages boss 313 and rigidly clamps it to lever 218.

In a direct line below slot 314, by which the slide member 207 is slidably supported upon stud 142, the slide member is provided with an open ended slot 316, the slot opening downwardly. Slot 316 is dimensioned to receive cylindrical boss 313 and to permit rotation of the boss within the slot or movement of the boss longitudinally thereof while affording substantially no lost motion of boss 313 transversely thereof. Boss 313 constitutes an articulation between lever 218 and slide member 207 so that when depending finger 221 of lever 218 is engaged by laterally extending projection 222 of the second function bar 193 from the top and lever 218 is rocked counterclockwise, slide member 207 will be shifted to its rearmost position.

For the restoration of slide member 207 to its foremost position, there is provided a lever 317 which is pivotally supported by stud 142 on the opposite side of slide member 207 from lever 218, and is provided at its upper end with an open ended slot 318. Slot 318 is adapted to receive the cylindrical portion of a boss 319 which is similar to boss 313 and which has a reduced portion 321 which enters an elongated slot 322 in slide member 207, located just below aperture 212. Screw 223 threadedly engages boss 319 and adjustably secures the reduced portion thereof in slot 322. Boss 319 constitutes an articulation between lever 317 and slide member 207, and when counterclockwise rotation is imparted to lever 317 by laterally extending projection 222 of the topmost function bar 193, slide member 207 is shifted from its rearmost to its foremost position. Screw 209, which, as previously described, passes through slot 208 in slide member 207 and guides it in the sliding movement which it is intended to receive, is engaged by a spring biased jockey 323 which is pivotally supported by slide member 207 at 324 and which is provided in its lower edge with spaced notches 326. Notches 326 in jockey detent 323 engage the shouldered portion of screw 209 and prevent accidental movement of slide member 207 out of a selected position to which it has been shifted. Since levers 218 and 317 are both pivoted on stud 142, and pivotally engage slide member 207 at points in opposite direction from stud 142, it will be apparent that each of the levers, upon being rotated by its associated function bar 193, imparts an opposite rotation to the other. The angular position of each of the levers with reference to slide member 207 in a predetermined position thereof may be varied by loosening the screws 219 and 223 and shifting the reduced portion of the bosses 313 and 319 in the slots 311 and 322 respectively.

Type wheel oscillating mechanism

Fig. 5 shows in complete detail the dual cam arrangement for controlling bail 131. The cams 125 and 186 are shown in their rest position, cam follower roller 293 engaging cam 125 at the minimum distance from the axis thereof, and cam follower roller 296 engaging the internal cam surface of cam 186 at the maximum distance from the axis thereof, so that bail 131 is in extreme clockwise position and type wheel supporting frame 139 is at its lowermost position. It being remembered that cam 125 rotates in counterclockwise direction and cam 186 in clockwise direction, when cam 125 begins to rotate, it shifts its follower roller 293 outwardly from the axis of shaft 103 and through arm 294, counterclockwise rotation is imparted to bail 131. Bail 131 has been rocked to extreme counterclockwise position as drop-off 133 of cam 125, which is a sharply descending cam surface, approaches follower roller 293. Before roller 293 moves down the drop-off 133, the clutch through which rotation is imparted to cam 186 is tripped off in a manner previously described, and cam 186 rotates in a clockwise direction through a sufficient angular distance to bring the cam surface portion which is at minimum distance from the axis of cam 186, which portion is identified by the reference numeral 331, into engagement with follower roller 296, whereby bail 131 is held in the position to which it had been rocked by cam 125. If cam 125 is not immediately set in rotation by the tripping of its driving clutch, it will remain in the position shown in Fig. 5 with cam follower roller 293 held out of engagement with cam 125 by the internal surface of cam 186. As cam 186 continues to rotate, the point of engagement of follower roller 296 with its internal cam surface recedes from the axis of the cam, thus controlling the return of bail 131 to extreme clockwise position. In this way, the control of bail 131 is transferred from one cam to the other in timed relation to the cycles of the two cams, and neither cam interferes with the operation of bail 131 by the other cam.

Cam assembly brake mechanism

In the lower portion of Fig. 5 there is shown in exploded perspective a series of elements which, when assembled, comprises a roller bearing grip clutch. Interposed between the main cam sleeve 130 and the shaft by which it is supported, there is a sleeve 331 which is fixed to sleeve 130 and is threaded at its lower end. The inner member 332 of a roller bearing grip clutch is threadedly secured to the lower end of sleeve 331. Member 332 fits into the central aperture of ring gear 106 and is retained in close proximity to the hub of gear 18, as shown in Fig. 3. Member 332 has a plurality of substantially right angled notches cut in the periphery thereof, the faces defining these notches being of unequal length, the shorter of the two faces of each notch designated by the reference numeral 333 extending substantially radially of the member 332. The angularly disposed faces of the notches and the adjacent arcuate inner surface of ring gear 106 define recesses that are generally triangular, being bounded by two plane surfaces and a curved surface. Each of the short faces 333 of the notches in member 332 is recessed to receive and support one end of a compression spring 334. An axially drilled roller bearing 336 is disposed in each of the generally triangular recesses and the com-

pression spring 334 tends to wedge the roller bearing between the long face of the notch and the arcuate internal surface of ring gear 106. The lower end of cam sleeve 130 is undercut to provide a shoulder 331 against which a retainer ring 338 is placed before member 332 is secured to sleeve 331. Retainer ring 338 fits loosely on the undercut portion of sleeve 130 and is not clamped in place, but is free to rotate. The purpose of ring 338 is to cover, at least partially, the rollers 336 and to prevent them from escaping from their respective recesses. There is a further purpose of ring 338, which will be described hereinafter.

Since roller bearings 336 cannot be inserted into their recesses after member 332 has been placed in position in ring gear 106, the retainer ring 338 preventing this, it is necessary to work the member 332 and rollers 336 into position in ring gear 106 at the same time. Springs 334 tend to complicate the bringing of the member 332 and rollers 336 into final position together, by urging the rollers 336 out of the positions in which they must be held in order to be inserted with member 332 into gear 106. The insertion of the rollers 336 and member 332 has been simplified by providing clearance recesses in ring gear 106, the recesses being cut partially into the inner surface of ring gear 106 and partially into the upper face thereof, thus providing inwardly sloping cam surfaces. With the assistance of the clearances 339, the rollers 336 may be worked partially into position individually, whereupon member 332 may be lowered into position in gear 106, the ring 338 urging rollers 336 down into position and the sloping cam surfaces of clearances 339 assisting in the insertion of the rollers.

Further simplification of the insertion of member 332 and rollers 336 into the recess in ring gear 106 has been afforded by the provision of depending fingers 341, integral with retaining ring 338. The axial bores of rollers 336 fit loosely on the depending fingers 341 of retainer ring 338, and when a roller 336 has been placed upon each of the fingers 341, all of the springs 334 may be partially compressed by rotating ring 338 in clockwise direction. Fingers 341 place restraint upon the movement of rollers 336, whereby they may be more easily cammed into position in their respective recesses by means of the clearances 339.

An understanding of the exact nature of the clutch by which cam sleeve 130 is driven is prerequisite to an understanding of the utility of roller bearing grip clutch consisting of member 332, rollers 336, and ring gear 106, the roller bearing clutch being used in the present invention as a brake. Cam sleeve 130 is driven by driving clutch element 124 and driven element 129 as previously described. This clutch mechanism is of the well-known one-way driving construction. Each tooth of both elements of the clutch has one surface substantially in a plane passing through the axis of the clutch, and the other surface oblique thereto. Should any torque be applied to the driven element 129 of the clutch which exceeds the torque applied to the driving element 124, the sloping surfaces of the teeth of one clutch element may tend to slide upon the sloping surfaces of the teeth of the other clutch element, thus shifting driven element 129 axially away from driving element 124 and compressing spring 126. If the differential between the two torques is appreciable, the driven element may be rotated ahead of the driving element a distance equal to the extent of several teeth of the

clutch members. A torque of sufficient magnitude to cause driven clutch element 129 to rotate more rapidly than driving element 124, and thus to gain upon it, may be generated by a heavily biased cam follower such as the function cam follower 199 and roller 201 or the print cam follower 153 and roller 152 riding down a sharply descending slope of their respective cams and thus becoming a negative load upon the driven clutch element 129.

The roller bearing grip clutch hereinbefore described serves as a brake to prevent acceleration of cam sleeve 130 under the influence of negative load upon any of its cams. Whenever cam sleeve 130 is stationary and the gears 78 and 106 are rotating, inner roller bearing clutch member 332, which is secured to sleeve 331 and, therefore, indirectly to cam sleeve 130, is also stationary, and the frictional engagement between the inner surface of ring gear 106 and rollers 336 tends to move the rollers into the widest portion of the recesses in which they are seated, the rollers thus being moved substantially free of inner clutch member 332 so that there is no tendency of gear 106 to impart rotation to the inner clutch member. When cam sleeve 130 is released for rotation and is rotating at the same speed as gear 106, there is no relative movement between roller bearing clutch member 332 and ring gear 106, and the springs 334 tend to wedge rollers 336 between the long faces of the notches in inner clutch member 332 and the inner surface of gear 106. If cam sleeve 130 should be subjected to a torque which tends to rotate it faster than gears 78 and 106, the frictional engagement of rollers 336 with member 332 tends to increase the wedging of the rollers between member 332 and gear 106 so that a positive lock between inner roller bearing clutch member 332 and gear 106 is established and cam sleeve 130 is prevented from accelerating in response to the locally applied torque and is held to the speed of rotation of gear 78.

Although specific embodiments of the features of invention have been disclosed and described herein, it will be understood that the invention is not limited to such specific embodiments but is capable of modification, reorganization, rearrangement and substitution of parts and elements without departing from the spirit of the invention and within the scope of the appended claims.

What is claimed is:

1. In a printing telegraph apparatus, a type wheel, means for rotating said type wheel, means for arresting said type wheel in selected positions, signal responsive means for controlling said arresting means, means for timing the control of said signal responsive means over said arresting means, means for printing from said type wheel, means for controlling said printing means, and means actuated by said timing means for setting in operation said controlling means.

2. In a printing telegraph apparatus, a type wheel, means for rotating said type wheel, means for arresting said type wheel in selected positions, signal responsive means for controlling said arresting means, means for effecting the control of said signal responsive means over said arresting means, means for printing from said type wheel, power driven means for controlling said printing means, and means actuated by said control effecting means for setting in operation said power driven means.

3. In a printing telegraph apparatus, a type wheel, means for rotating said type wheel, means

for arresting said type wheel in selected positions, signal responsive means for controlling said arresting means, power driven means for conditioning said arresting means to arrest said type wheel, power driven means for controlling printing from said type wheel, and means operable during a cycle of operation of said conditioning means for setting in operation said printing controlling means.

4. In a printing telegraph apparatus, a type wheel, means for rotating said type wheel, permutation code means for arresting said type wheel in selected positions, means for receiving and storing permutation code signals, means for transferring the setting of said signal storing means to said type wheel arresting means, power driven means for actuating said transferring means, means for printing from said type wheel, and power driven means set in operation by said first mentioned power driven means after the operation of said transferring means for controlling said printing means.

5. In a printing telegraph apparatus, a type wheel, means for rotating said type wheel, a signal receiving selector, a type wheel controlling selector, means for printing from said type wheel, independently driven means for setting said type wheel controlling selector and for controlling said printing means, one of said driven means being set in operation by said signal receiving selector and in turn setting in operation the other of said driven means.

6. In a printing telegraph apparatus, a type wheel, means for rotating said type wheel, a signal receiving selector operable in cycles, a type wheel controlling selector, means for printing from said type wheel, individually driven means set in operation by said signal receiving selector for setting said type wheel controlling selector, and individually driven means set in operation by the last mentioned means for controlling said printing means.

7. In a printing telegraph apparatus, a type wheel, means for rotating said type wheel, a signal receiving selector, a type wheel controlling selector, means for printing from said type wheel, means effective when set in operation by said signal receiving selector for setting said type wheel controlling selector, and means effective when set in operation by said last mentioned means for controlling said printing means.

8. In a printing telegraph apparatus, a type wheel, means for rotating said type wheel, a signal receiving selector mechanism, a type wheel arresting selector mechanism, means for printing from said type wheel, a power driven distributor operable in cycles in said signal receiving selector mechanism, power driven means for setting said type wheel arresting selector mechanism, means power driven independently of said first mentioned power driven means for controlling the operation of said printing means, means controlled by said distributor in each cycle thereof for setting in operation the first mentioned power driven means, and means controlled by said first mentioned power driven means in each cycle thereof for setting in operation the second recited power driven means.

9. In a printing telegraph apparatus, a type wheel, a rotatable shaft, means for slidably supporting said type wheel upon said shaft, means for printing from said type wheel, power driven means for shifting said type wheel into printing position before a printing operation, means for retracting said type wheel, and means power 75

driven independently of said first mentioned power driven means for controlling the retraction of said type wheel by said retracting means after a printing operation.

5 10. In a printing telegraph apparatus, a type wheel, an oscillatable support for said type wheel, a printing member mounted to be substantially immovable in the direction of oscillation of said type wheel support, power actuated means for moving said support to bring said type wheel into position to be acted upon by said printing member, and other power actuated means for positively and unyieldably imparting retracting movement of controlled velocity to said support.

10 15 20 25 11. In a printing telegraph apparatus, a type wheel, an oscillatable support therefor, power driven means for shifting said support with controlled velocity in one direction and thereafter relinquishing control over said support, and other power driven means for assuming positive control over said support after the movement thereof in one direction and for controlling unyieldably the velocity of movement of said support in the opposite direction.

12. In a printing telegraph apparatus, a type wheel, a shiftable support for said type wheel, a shifting bail connected to said support, a plurality of cam followers carried by said bail, and a plurality of independently driven cams to be engaged by and control said followers individually.

25 30 35 13. In a printing telegraph apparatus, a type wheel, a shiftable support therefor, a shifting bail connected to said support, a plurality of cam followers carried by said bail, a plurality of independently driven cams for controlling said cam followers individually, and means for setting said cams in operation successively in overlap relation.

40 45 14. In a printing telegraph apparatus, a type wheel, a shiftable support for said type wheel, a shifting bail connected to said support, a plurality of cam followers carried by said bail, a power driven mechanism including a cam for controlling one of said cam followers, an independently driven mechanism including a cam for controlling another of said cam followers, and means included in the first mentioned power driven mechanism for setting in operation the second mentioned mechanism.

50 55 60 15. In a printing telegraph apparatus, a type wheel, a type wheel shaft, means on said shaft for supporting said type wheel, means accessible from the top of said type wheel for removably securing said type wheel to said supporting means, means for printing from said type wheel reciprocably supported above said type wheel, means for actuating said printing means, and means for articulating said printing means to said actuating means having a horizontally disposed axis, whereby said printing means may be rocked in a vertical plane away from said type wheel for permitting access thereto.

65 16. In a printing telegraph apparatus, a type wheel, means for printing from said type wheel, and means for reciprocably supporting said printing means, said supporting means including a pivotal articulation having its axis substantially normal to the axis of said type wheel and to the direction of reciprocation of said printing means, whereby said printing means may be rocked out of printing position for permitting access to said type wheel.

17. In a printing telegraph apparatus, a type wheel, means for rotating said type wheel, a signal receiving selector operable in cycles, a

type wheel controlling selector, means for printing from said type wheel, individually driven means set in operation by said signal receiving selector for setting said type wheel controlling selector according to the signal then in control of said signal receiving selector, and individually driven means set in operation by the means for setting the type wheel controlling selector for controlling said printing means.

18. In a printing telegraph apparatus, a type wheel, a signal receiving selector mechanism operable in cycles, a type wheel controlling selector, means for printing from said type wheel, individually driven means set in operation by said signal receiving selector mechanism for setting said type wheel controlling selector according to the signal then in control of said signal receiving selector mechanism, means for rotating said type wheel to a selected position according to the setting of the type wheel controlling selector, and individually driven means set in operation by the means for setting the type wheel controlling selector for controlling said printing means to effect printing according to the selected position of the type wheel.

19. In a printing telegraph apparatus, a type wheel, means for rotating said type wheel, a signal receiving selector operable in cycles, a type wheel controlling selector, means for printing from said type wheel, means set in operation by said signal receiving selector and effective when the signal receiving selector has completed a cycle for setting said type wheel controlling selector, and means set in operation by said last mentioned means and effective after the operation of the last mentioned means for controlling said printing means.

20. In a printing telegraph apparatus, a type wheel, means for rotating said type wheel, a signal receiving selector, a type wheel controlling selector, means for printing from said type wheel, means for setting said type wheel controlling selector, means for driving said setting means, means controlled by said signal receiving selector for connecting said setting means to said driving means, means for controlling said printing means, means for driving said controlling means, and means controlled by said selector setting means for connecting said printing controlling means to the second mentioned driving means.

21. In a printing telegraph apparatus, a type wheel, means for printing from said type wheel, means for shifting said type wheel into position for co-operation with said printing means and

for retracting said type wheel, means for imparting controlled type wheel shifting motion to said shifting means, and other means for positively imparting controlled type wheel non-yieldable retracting motion to said shifting means.

5 22. In a printing telegraph apparatus, a type wheel, an oscillatable support for said type wheel, power driven means for shifting said support in one direction and thereafter relinquishing control over said support, and other power driven means for maintaining said support in said shifted position and for thereafter shifting it in the opposite direction.

10 23. In a printing telegraph apparatus, a type wheel, an oscillatable support for said type wheel, power actuated means for shifting said support in one direction and thereafter relinquishing control over said support, and other power actuated means set in operation by the first mentioned power actuated means before the relinquishment of control by the first mentioned power actuated means for maintaining said support in said shifted position and for thereafter shifting it in the opposite direction.

15 24. In a printing telegraph apparatus, a type wheel, a shiftable support for said type wheel, a shifting bail connected to said support, a plurality of cam followers carried by said bail, a power driven mechanism including a cam operable upon one of said followers for actuating said bail to one position, an independently driven mechanism including a cam operable upon the other follower for returning said bail to its original position, and means included in the first 20 mentioned power driven mechanism for setting in shifted position and for thereafter shifting it in the opposite direction.

25 25. In a printing telegraph apparatus, a type wheel, a shiftable support for said type wheel,

40 a shifting bail connected to said support, a plurality of cam followers carried by said bail, a power driven mechanism including a cam operable upon one of said followers for actuating said bail to one position and thereupon relinquishing control over said follower, an independently driven mechanism including a cam operable upon the other follower for holding said bail in the position to which it had been actuated and thereafter returning said bail to its original position, and means included in the first mentioned power driven mechanism for setting in operation the second mentioned driven mechanism.

ALBERT H. REIBER.
